CENTRIFUGAL CASTING MACHINE FOR
CASTING HOLLOW METAL BODIES

Clarence D. Barr and Stephen D. Moxley, Birmingham, Ala., assignors to Sand Spun Patents Corporation, New York, N. Y., a corporation of Delaware

Application January 12, 1932, Serial No. 586,220

4 Claims. (Cl. 22—65)

This invention relates to centrifugal casting machines for casting hollow metal bodies, such as cast-iron pipe in refractory or sand-lined flasks, and wherein a separate flask is employed for each 5 cast.

In casting machines of this type, the flask is usually supported upon rollers and is rotated by means of an electric motor, having a clutch upon its shaft which may be removably coupled to the 10 end of the flask for rotating the same.

It has been proposed to employ a magnetic clutch to drive the flask, but in such proposed construction no provision has been made to accurately align the clutch-face with the end of the 15 flask, or to provide a construction wherein the magnetic clutch may be so mounted as to be properly aligned with flasks of different diameter.

The object of the present invention is to provide a centrifugal casting machine of the type 20 referred to that may accommodate flasks of different diameter, and wherein the motor and the magnetic clutch are so mounted upon the bed of the machine that they may be readily adjusted both vertically and laterally to bring the magnetic 25 face of the clutch into proper alignment with an end of the flask, the said motor and its clutch mounting being so constructed and arranged that they may be adjusted vertically and laterally to align the clutch face with an end of the flask.

30 In order to enable others skilled in the art to construct and use the said invention, we will now proceed to describe the same in detail, reference being had for this purpose to the accompanying drawings, wherein,—

35 Fig. 1 is a side elevation of a part of a centrifugal casting machine, having our invention embodied therein,

Fig. 2 is a top plan view, and

Fig. 3 is an end elevation.

40 In the accompanying drawings, the reference character 1 designates the heavy metal base casting of a centrifugal casting machine which is usually supported upon concrete or other foundation. The machine also embodies two pairs of 45 spaced flask-supporting rollers 2, for supporting the flask 3 for rotation; the reference character 4 indicating the end of the flask against which the face of a magnetic clutch 5 makes direct contact.

50 The base casting 1 has an extension 1a at one end, provided with two pairs of upstanding projections 6 and 6a, the projections 6 being located adjacent the end of the extension 1a, and spaced apart, as more clearly shown in Fig. 2, and the 55 projections 6a are likewise spaced apart, as shown

in Fig. 2, and are arranged adjacent the end of the casting machine proper.

The reference numeral 7 indicates an electric motor having its shaft 8 journaled in bearings 9 and upon the forward end of which the magnetic clutch 5 is secured. The motor shaft 8 is preferably made in alined sections, which sections are preferably connected together by a flexible coupling 10 of any preferred type.

The motor 7 and its shaft bearings 9 are mounted upon an auxiliary frame, comprising a metal plate 12, secured to the base casting by means of bolts 13 and 14, the bolts 13 passing thru lateral frame extensions 12' at opposite sides of the frame 12 adjacent the flask 4, of the machine, and the 70 bolt 14 passing through the extreme end of the auxiliary frame 12 and the base extension 1a, as more clearly shown in Fig. 2.

The auxiliary frame 12 is supported upon interposed shims or filler blocks 15, removably 75 mounted upon the base extension 1a adjacent the bolts 13 and 14, the thickness thereof determining the height of the auxiliary frame 12 and the position of the magnetic clutch 5, relative to the end of the flask 3. By interchanging the 80 filler blocks 15 and substituting thinner or thicker blocks as occasion may demand, it will be apparent that the face of the magnetic clutch 5 may be accurately adjusted and centered to cooperate with flasks of different diameter.

85 In order to provide for lateral adjustment of the auxiliary frame 12, to more accurately align the face of the magnetic clutch 5 with the end of a flask, we provide each of the upstanding projections 6 and 6a, with bolts 16, the inner ends of 90 which may be brought into engagement with the opposite sides of the auxiliary frame 12, and the bolts then set by means of lock nuts 17. In the construction shown, the bolts 16 which pass through the projections 6a, may contact with the 95 lateral extensions 12' of the auxiliary frame 12, and those which pass through the projections 6 engage the upstanding flanges 18 of the auxiliary frame 12.

100 It will be apparent from the foregoing that the auxiliary frame 12, which carries the motor 7, shaft 8, bearings 9, and the magnetic clutch 5, may be vertically and laterally adjusted to bring the face of the clutch into accurate alignment with the ends of flasks of different size, thus 105 adapting one machine to the manufacture of pipes of various sizes.

110 While we have illustrated and described a preferred embodiment of our invention, we do not wish to be understood as limiting ourselves to

the various details shown, as obviously these may be varied without departing from the spirit of the invention, which resides broadly in mounting the magnetic clutch and its driving motor upon a support which may be adjusted both vertically and laterally for the purposes stated.

What we claim is:—

- 5 1. In a centrifugal casting machine having a base platform and means for supporting a flask for rotation, means for driving the flask including a motor-driven magnetic clutch having a face adapted to contact with an end of a supported flask, a bodily movable auxiliary platform supported upon the base platform and constituting a support for the clutch-driving motor located at one end of and in alignment with the casting machine, a driving motor and motor-shaft bearings carried by said auxiliary platform and means for adjusting the auxiliary platform vertically and laterally to center the face of the clutch relative to the end of the supported flask, and means to positively lock said last means against movement during rotation of the clutch and flask.

- 20 2. In a centrifugal casting machine having means for supporting a flask for rotation and a bed plate, a bodily movable platform to support an electric motor, said motor having a magnetic clutch secured to its shaft, means to adjust the position of said motor, shaft and clutch to establish the axis of the clutch in alignment with the axis of the flask, said means comprising interchangeable filler blocks between the auxiliary platform and bed plate to establish the axis of the clutch in alignment with the axes of the flask in a horizontal plane, upstanding members at opposite sides of the bed plate between which the auxiliary platform is supported on the filler blocks, screw threaded elements mounted through screw threaded openings in said members to contact the sides of said platform and operable to move said platform laterally to establish the axes of the clutch and flask in a common vertical plane, the sides of said platform confronting said members and elements being provided with upstanding flanges for engagement by said screw threaded elements.

- 25 3. In a centrifugal casting machine having means for supporting a flask for rotation and a bed plate, a bodily movable platform to support an electric motor, said motor having a magnetic clutch secured to its shaft, means to adjust the position of said motor, shaft and clutch to establish the axis of the clutch in alignment with the axis of the flask, said means comprising interchangeable filler blocks between the auxiliary platform and bed plate to establish the axis of the clutch in alignment with the axis of the flask in a horizontal plane, upstanding members at opposite sides of the bed plate between which the auxiliary platform is supported on the filler blocks, screw threaded elements mounted through screw threaded openings in said members to contact the sides of said platform and operable to move said platform laterally to establish the axes of the clutch and flask in a common vertical plane, the sides of said platform confronting said members and elements being provided with upstanding flanges for engagement by said screw threaded elements.

- 30 4. In a centrifugal casting machine, an adjustable supporting means for a clutch and motor to rotate the flask of the centrifugal casting machine, comprising a bed plate, a bodily movable platform to support the motor and clutch, interchangeable blocks between the platform and bed plate to establish the axis of the clutch in alignment with the axis of the flask in a horizontal plane, upstanding members on the bed plate at opposite sides thereof and between which the platform is located, screw threaded elements mounted through screw threaded openings in said members to contact the sides of said platform and operable to move said platform laterally to establish the axes of the clutch and flask in a common vertical plane, and means to lock said elements in adjusted position during rotation of the flask.
